MOLDED PULP ARTICLE

Merle P. Chaplin, South Portland, Maine, assignor to Chaplin Corporation, South Portland, Maine, a corporation of Maine

Application May 26, 1937, Serial No. 144,905

6 Claims. (Cl. 229—2.5)

This invention relates to improvements in a molded pulp article disclosed in my copending application Serial No. 113,308, filed Nov. 30, 1936.

This article is die molded from a liquid pulp mixture on contoured suction dies and certain portions of the article are so subdivided and shaped that they may be reformed into a new position or location to form a useful article of commerce.

10 The article as die molded, is so shaped that successive articles may be nested and stacked with each other to form a minimum of shipping space for delivery to the consumer. After being received these articles may be readily reshaped, and held in reshaped position forming a new and useful container.

This application has to do with improvements on the article, itself, and principally with the divided edge portion.

15 In the design previously disclosed, no provision was made in the design of the divided edge portion, to insure that this portion, when reshaped, formed a perfect circle or rested flat and uniformly on its support. Certain further improvements in the locking edge construction have been found desirable in order to make the lower edge portions of the reshaped article more sturdy and to provide for better stacking of superimposed reshaped article.

20 Reference is made to the following figures:

Fig. 1 is a half plan view of the article before reshaping.

Fig. 2 is a side view of the article of Fig. 1 half in section, taken on line 2—2, Fig. 1, the other half, an exterior view.

25 Fig. 3 is a plan view of two adjacent edge sections before reshaping.

Fig. 3—a is a sectional view thru the center of the slot of Fig. 3, or as indicated at line 3—a, Fig. 1.

30 Fig. 4 is a plan view of the sectional edge of the article after it has been partially reshaped.

Fig. 4—a is a sectional view thru the slot of Fig. 4.

35 Fig. 5 is a plan view of the sectional edge of the article after reshaping.

Fig. 5—a is a sectional view on line with the closed slot of Fig. 5.

40 Fig. 6 is a view showing one reshaped article with its retaining band superimposed on a similar article.

Fig. 7 is a view showing a modification of divided edge construction to facilitate stacking.

45 The molded pulp article herein disclosed, consists of a flat, central section 19, an upwardly and

outwardly inclined section 18, and a flange portion 17. Molded integrally with this flange portion 17, are a plurality of edge sections 15, separated by slots or notches 14. These divided sections 15, terminate at their outer ends in an angle-shaped formation consisting of an outwardly and somewhat upwardly projecting portion 20, and an outwardly and somewhat downwardly projecting portion 21.

5 The present invention resides largely in the shape, construction and utility of the extending edge portions 15, and the angle portions 20 and 21. It will be understood that the central portions 18 and 19, together with the rim portions 17 can be made any desired shape or depth in accordance with the use to which the reshaped article may be put. The particular design illustrated is only one of many different shapes which might be employed.

20 The article illustrated in Figs. 1 and 2, after being die molded and dried, is shipped to the consumer in closely nested bundles or stacks. After being received, each molded pulp article is removed from the nested stack and the extended edge portions, hereinafter described, are 25 reformed or reshaped, being bent or folded on lines 16, into a new position bringing their segmented edge portions into mutually abutting and alining relation and forming a substantially continuous rim about the periphery of the article, 30 extending in a vertical direction normal to its base, and adapted to support the container portion of the article rigidly and firmly. The reshaped portions may be held in place by a ring or band which, in turn, may be further utilized 35 to support another reshaped article.

40 In my prior disclosure I provided an angle-shaped formation on the end of sectional members 15, which, when reshaped, form substantially a right-angle portion or locking section about the edge of the article. While this provided a reasonably satisfactory construction and design, it was found that under extreme conditions in the handling of the reshaped article, that even though the adjacent edges of extending portions 15, were abutted firmly together when the article was reshaped, that it was sometimes possible to push one of these sections inwardly and away from the retaining band and partially destroy the abutting or compression effect of 45 several sections 15, one against the other.

45 It will be noted that in the design disclosed herewith the section 20 and the section 21, form an acute-angle instead of a substantially right-angle as shown in my prior application. This de- 55

sign permits a double locking of the sections 15, as is more particularly illustrated in Fig. 6. In this figure the extended edge portions 15, have been reshaped into substantially vertical position and are held reshaped by a band member 23.

Not only does this band member 23, restrain the segmental edge portions 15 from resuming their original position, as shown in Figs. 1 and 2, but also holds sections 15 in mutually abutting relation. This construction also prevents sectional portions 15, from being pushed out of line inwardly, by a locking action between the flange portion 20 and the band 23. Thus, the design disclosed herein, provides for a more rigid and sturdy stacking edge portion than my prior disclosure.

In my prior disclosure, the edge portions 20 and 21, of sectional portions 15, presented a true circle before said sections were reshaped. Consequently, when these sections were reshaped inwardly and downwardly, they no longer assumed a true circle, nor did their lower edges rest flat on a supporting surface or on a supporting band. On the contrary, they presented a scalloped appearance after reshaping, each extended edge portion curving downwardly and outwardly in its center, presenting a somewhat unsightly appearance and failing to provide as much supporting surface as desirable. Such a condition is particularly undesirable where the angle portion is utilized to lock the edge portions 15, against both inward and outward movements.

It is, therefore, necessary to initially mold the angle portions 20 and 21, together with the adjacent portion of part 15, so that they curve upwardly at point 26, and somewhat inwardly, in order that they may present a true circle when reshaped, and lie flat on the table or other supporting member.

To illustrate this, reference is made to Figs. 3 and 3-a, 4 and 4-a and 5 and 5-a.

In Figs. 3 and 3-a the extended edge portion 15 is shown in its un-reshaped condition or in a condition in which the molded article is shipped to the consumer. Slot 14 has not been reduced in size and this portion, together with the portions 20 and 21, in the position shown in Figs. 3 and 3-a, permit the articles to be nested.

In use, the extended edge portions 15 are brought into substantially vertical position and Figs. 4 and 4-a, show this operation approximately one-half completed. Slot 14 has become partially closed and the curved portion 26, between the ends 27 of parts 15, has assumed a partially flat position. Continuing the reshaping of the extended portions 15, brings the ends 27 of mutually adjoining sections 15 into abutting relation, and the slot 14 is closed at its bottom end. Under these conditions, as shown in Fig. 5-a, the bottom surface of the edge portions 20 and 21, has assumed a substantially straight line from the ends 27 thru the center 28, affording a complete uniformly flat surface on which the article may be supported, thus avoiding the uneven support and scalloped effect of my previous design.

A further improvement found desirable in some instances, is disclosed in Fig. 7. This improvement is to facilitate the stacking of superimposed articles and, particularly, to insure an additional centering and locking effect of a superimposed article on the band of a sub-adjacent article. In this modified design shown in Fig. 7, the extended edge portion 15, instead of being perfectly straight, is molded at its lower edge adjacent

to section 20, with an inwardly projecting section 15-a. This enables the inner part of section 20 at point 28, to be moved inwardly, relative to the band 23, so that the upper end of this band, when the article is resting thereon, will be somewhat restrained against inward movement and, further, will have some tendency to move outwardly when a superimposed article is placed thereon, due to the tapering character of the bottom surface of section 20.

The outward movement of band 23 will be limited by section 21, and the V-shaped form of sections 20 and 21 indicated at point 28, will form an efficient locking and centering means for superimposing articles, preventing them when stacked, from being easily shaken out of place. The effectiveness of the modified design illustrated in Fig. 7 over that illustrated in Fig. 6 so far as centering and locking stacked articles is concerned is readily apparent.

Having thus described my invention what I claim is:

1. A fibrous container comprising a bottom, an outwardly and upwardly flared wall encompassing said bottom, a flange integral with said flared wall and extending outwardly therefrom, said flange having slots extending inwardly from the edge thereof to points adjacent said flared wall and dividing said flange into spaced sections, each section being bendable along a line adjacent said flared wall to a reshaped and reformed position, and being slightly concaved from slot to slot adjacent its edge, whereby when said sections are bent into a substantially vertical position, they will form a circle and lie flat on a supporting member.

2. A fibrous container comprising a bottom, an outwardly and upwardly flared wall encompassing said bottom, a flange integral with said flared wall and extending outwardly therefrom, said flange having slots extending inwardly from the edge thereof to points adjacent said flared wall and dividing said flange into spaced sections, each section being slightly concaved from slot to slot adjacent its edge, and said sections having a reverse bend along their outer edges forming an acute, angularly conformed recess adjacent said edges for reception of a restraining band effective to prevent the sectional edge portions from moving outwardly or inwardly.

3. A fibrous container comprising a bottom, an outwardly and upwardly flared wall encompassing said bottom, a flange integral with said flared wall and extending outwardly therefrom, said flange having slots extending inwardly from the edge thereof to points adjacent said flared wall and dividing said flange into spaced sections, each section being slightly concaved from slot to slot adjacent its edge, and said sections having a reverse bend along their outer edges forming an acute, angularly conformed recess adjacent said edges for reception of a restraining band effective to prevent the sectional edge portions from moving outwardly or inwardly, and a downwardly projecting portion substantially parallel to the flange externally spaced therefrom to provide a seat for the reception of a duplicate assembly.

4. A fibrous container comprising a bottom, an outwardly and upwardly flared wall encompassing said bottom, a flange integral with said flared wall and extending outwardly therefrom, said flange having slots extending inwardly from the edge thereof to points adjacent said flared wall and dividing said flange into spaced sections, each section being slightly concaved from slot to

- slot adjacent its edge, and said sections having a reverse bend along their outer edges forming an acute, angularly conformed recess adjacent said edges for reception of a restraining band effective to prevent the sectional edge portions from moving outwardly or inwardly, and a restraining band seated in said recess, said band being of greater width than the overall height of the container, positioned to encompass said sections and to extend substantially above the top of the container for seating in the angularly conformed recess of a duplicate assembly.
5. A fibrous container comprising a bottom, an outwardly and upwardly flared wall encompassing said bottom, a flange integral with said flared wall and extending outwardly therefrom, said flange having slots extending inwardly from the edge thereof to points adjacent said flared wall and dividing said flange into spaced sections, each section being slightly concaved from slot to slot adjacent its edge, and said sections having a reverse bend along their outer edges forming an acute, angularly conformed recess adjacent said edges for reception of a restraining band effective to prevent the sectional edge portions from moving outwardly or inwardly, and a restraining band seated in said recess, and
- 10 a downwardly projecting portion substantially parallel to the flange externally spaced therefrom, to provide a seat for the reception of a duplicate assembly, said band being of greater width than the overall height of the container, positioned to encompass said sections and to extend substantially above the top of the container for seating in the angularly conformed recess of a duplicate assembly.
- 15 6. A fibrous container comprising a bottom, an outwardly and upwardly flared wall encompassing said bottom, a flange integral with said flared wall and extending outwardly therefrom, said flange having slots extending inwardly from the edge thereof to points adjacent said flared wall 15 and dividing said flange into spaced sections, each section being slightly concaved from slot to slot adjacent its edge, and said sections having a reverse bend along their outer edges forming an angular conformation at said edges, the extreme outer edge portion of each section between its reversely bent portion and the flared wall being bent inwardly to a greater angle with respect to the flared wall, than the remainder of said section.
